MEASURING VALVE

Lawrence M. White, Los Angeles, Calif.

Application March 9, 1946, Serial No. 653,417

3 Claims. (Cl. 222—442)

1

This invention relates to a measuring valve as particularly directed to a device including a valve for measuring a predetermined quantity of liquid from a container.

The principal object of this invention is to provide a measuring valve for measuring a quantity of liquid which is positive in action and may be manually controlled by one hand.

Another object is to provide a measuring valve of this type in which the volume of fluid dispensed may be varied at will.

Another object is to provide a measuring valve of this type adapted to be inserted within the neck of a container and which employs a flexible diaphragm to seal off a chamber within the container neck.

Another object is to provide a device for measuring a predetermined quantity of liquid from a container which employs a novel vent means for facilitating flow from a chamber defined within the container.

Other objects and advantages will appear hereinafter.

In the drawings:

Figure 1 is a side elevation, partly in section, showing a preferred embodiment of my invention and illustrating the position of my device with respect to a container for fluid.

Figure 2 is a longitudinal sectional view showing the various detail parts of the device on a larger scale.

Figure 3 is a sectional view taken on the line 3—3 as shown in Figure 2.

Figure 4 is a sectional view similar to Figure 3 but illustrating the parts in another position.

Figure 5 is a sectional view taken substantially on the line 5—5 as shown in Figure 2.

Referring to the drawings, the container 10 having a neck 11 is normally provided with an external thread 12 adjacent its outlet 13. In accordance with my invention, I provide a cylindrical body 14, having internal threads 15 adapted for engagement with the container threads 12. A gasket 16 may be provided between the end of the neck 11 and the body 14 if desired. Secured on the upper end of the body 14 as by threads 17 is a stationary cap 18 provided with a discharge port 19. Secured centrally of the cap 18 is the depending tubular guide 20 extending downwardly through the body 14 and into the neck 11 of the container 10. Secured to the body 14 concentrically with the guide 20 is the inner valve sleeve 21 which terminates in a shoulder 22 which encircles the guide 20. Ports 23 are formed through the wall of the valve sleeve 24

2

21. An outer valve sleeve 24 is arranged to slide on the inner valve sleeve 21 and is provided with ports 25 which are adapted to align with the ports 23 when the outer valve sleeve 24 is in its upper position.

22. A pin 26 is secured to the shoulder 22 of the inner sleeve 21 and projects downwardly through a recess 27 formed through the shoulder 28 at the lower end of the outer valve sleeve 24. The purpose of this pin 26 is to prevent relative rotation between the valve sleeve 21 and 24. Threadedly connected to the shoulder 28 on the outer valve sleeve 24 is the spring housing 29 which encircles the tubular guide 20 to define an annular recess 30. A compression spring 31 is positioned within this annular recess 30 and is confined between the shoulder 22 on the inner valve sleeve 21 and the shoulder 32 at the lower end of the spring housing 29.

23. Threadedly secured to the lower end of the spring housing 29 is the vent pipe 33 and at the lower end of the vent pipe 33, the hollow extension rod 34 is secured and fastened by means of the lock nut 35. At the lower end of the hollow rod 34 is a circular flexible disc 36. A screw 37 and washer 38 are used in securing the disc 36 to the lower end of the hollow rod 34. The disc is made flexible for several reasons as will appear hereinafter and in order that it may be inserted through the restricted outlet 13 and neck 11 of the container 10.

24. A hollow cup element 39 is secured to the hollow rod 34 by means of the nut 40 and acts as a stiffener element supporting the flexible disc 36.

25. Means are provided for actuating the valve sleeve 24 to bring the valve ports 23 and 25 into alignment, and as illustrated such means include a bifurcated post 41 secured on the cap 18 and carrying a pin 42 for pivotally supporting an actuating crank 43. A thumb pad 44 is provided on one end of the crank 43 and at the other end the crank 43 is pivotally connected to an actuating rod 45 which extends downwardly through the opening 46 at the upper end of the cap 18 and through the tubular guide 20. The lower end of the actuating rod 45 is threadedly received in a dam element 38a threaded into the vent pipe 33.

26. From the above description it will be understood that when the actuating crank 43 is moved from its normal position, as indicated by the dotted lines in Figure 1, to the position indicated by the solid lines, the rod 45, together with the vent pipe 33, spring housing 29, and outer valve sleeve 24, is lifted vertically. This lifting motion

brings the ports 25 from their inoperative position to their position of alignment with the ports 23, thereby establishing a flow path from the interior of the neck 11 to the discharge port 19. The same lifting action by the rod 45 serves to lift the hollow rod 34 secured on the lower end of the vent pipe 33 and thus bring the flexible disc 36 from its normal inoperative position, as indicated by the dotted lines in Figure 1, to its operative position indicated by the full lines.

In its operative position the flexible disc 36 contacts the inside of the container 10 to form a seal and to define a measuring chamber 47 within the neck 11 of the container 10 and between the disc 36 and the upper end of the stationary body 14. When the container is inverted from the position shown in Figure 1 and when the thumb pad 44 is actuated to bring the valve ports 25 and 23 into alignment, the disc 36 prevents additional flow of fluid from the interior of the container 10 into the chamber 47 within the neck portion 11 so that only the fluid within the chamber 47 is discharged through the port 19.

Means are provided for venting the chamber 47 during the interval of discharge therefrom in order to bring air into the neck of the container and thus facilitate discharge through the port 19. As shown in the drawings, this vent means includes the opening 48 in the upper end of the cap 18 and the annulus 48 between the actuating rod 45 and the tubular guide 28. The vent passage, which includes the annulus 48, continues downwardly through the vent pipe 33 through the passages 49 formed through the dam 38a and into the hollow rod 34. The lower end of this vent passage terminates in vent ports 50 drilled laterally into the lower end of the hollow rod 34. The ports 50 lead into an annular space within the cup member 39. When the fluid within the chamber 47 is being discharged through the port 19, air from the atmosphere is admitted through the vent passage including the annulus 48 and hollow rod 34 and flows outwardly through the ports 50 into the annular space 51. Since the pressure of the fluid within the chamber 47 adjacent the disc 36 is somewhat below atmospheric pressure during the interval of discharge, the air admitted into the space 51 escapes radially outwardly past the flexible disc 36 and into the chamber 47. The discharge of fluid through the port 19 is therefore rapid and efficient.

When the measuring valve assembly is initially inserted into the neck of container 10, the flexible disc 36 cooperates with the rim on the cup member 39 to prevent entry of liquid into the annular space 51, and hence no liquid enters the vent passage. When the container is inverted, the chamber 47 fills with liquid, but the seal between the flexible disc 36 and the cup member 39 again prevents entry of liquid into the vent space 51. Actuation of the thumb pad 44, however, serves to flex the disc 36 against the inside of the container wall and thereby materially diminish the sealing effect between the flexible disc and the cup member 39. With the sealing effect thus partially destroyed, the air within the annulus 51 at atmospheric pressure has no difficulty in flowing outwardly into the chamber 47. It is therefore apparent that the action of the flexible disc 36 in forming a seal with the cup member 39 insures that a volume of air will always be present within the annulus 51. This air is instantly available at time of discharge to enter the chamber 47 and hence to promote nonturbulent flow of liquid from the discharge orifice 19.

While the container 10 is held inverted in pour-

ing position a number of small glasses may be filled, discharging the same amount of liquid into each glass. It is not necessary to re-invert the container in order to fill each glass. When the liquid in the chamber 47 has been discharged into the first glass, the thumb pad 44 is released to permit the spring 31 to close the ports 25 and 23 and then to move the flexible disc 36 out of contact with the inside of the container 10. The air in the chamber 47 which entered through the vent passage is then displaced by fluid entering the chamber 47 from the main part of the container 10. The disc 36 and rim on the cup element 39 cooperate to prevent entry of fluid into the vent passage while the chamber 47 is filling.

In order to change the volume of fluid contained within the measuring chamber 47, a displacement element 52 may be provided which is received on the rod 34. The displacement element 52 is formed of a size to displace the proper amount of fluid, and if necessary may extend upwardly to cover all or a portion of the spring housing 29, as well as the rod 34, as will be readily understood.

Having fully described my invention, it is to be understood that I do not wish to be limited to the details herein set forth, but my invention is of the full scope of the appended claims.

I claim:

30. 1. For use in conjunction with a fluid container having a neck provided with an outlet, a dispensing device comprising in combination: a stationary member provided with a discharge port and removably secured to the container within the outlet, a sleeve valve element fixed on the stationary member, a movable member mounted on the stationary member and projecting into the container, a sleeve valve element fixed on the movable member, ports on the sleeve valve elements adapted to be aligned when the movable member is in open position, a flexible sealing disc secured on the projecting end of the movable member and adapted to contact the inside wall surface of the container when the movable member is in open position to define a measuring chamber within the neck of the container between the sealing disc and the stationary member, resilient means normally acting to maintain the movable member in closed position, and means to move the movable member to open position.

2. For use in conjunction with a fluid container having a neck provided with an outlet, a dispensing device comprising in combination: a stationary member provided with a discharge port and removably secured to the container within the outlet, a sleeve valve element fixed on the stationary member, a movable member mounted on the stationary member and projecting into the container, a sleeve valve element fixed on the movable member, ports formed in the sleeve valve elements adapted to be aligned by movement of the movable member, a flexible sealing disc secured on the projecting end of the movable member and adapted to contact the inside wall surface of the container when the valve ports are in aligned position, the said disc in sealing position acting to define a measuring chamber within the neck of the container between the sealing disc and the stationary member, means for actuating the movable member to bring the valve ports into alignment to permit gravity flow from the chamber through the discharge port, and vent means associated with the movable member communicating with the atmosphere and

terminating within the said chamber at a location adjacent to the flexible sealing disc.

3. For use in conjunction with a fluid container having a neck provided with an outlet, a dispensing device comprising in combination: a stationary member provided with a discharge port and removably secured to the container within the outlet, a sleeve valve element fixed on the stationary member, a movable member mounted on the stationary member and projecting into the container, a sleeve valve element fixed on the movable member, ports formed in the sleeve valve elements adapted to be aligned by movement of the movable member, a flexible sealing disc secured on the projecting end of the movable member and adapted to contact the inside wall surface of the container when the valve ports are in aligned position, the said disc in sealing position acting to define a measuring chamber within the neck of the container between the sealing disc and the stationary member, resilient means normally acting to maintain the valve ports in inoperative position, means positioned

exteriorly of the container for actuating the movable member to bring the valve ports into alignment to permit gravity flow from the chamber through the discharge port.
